UNITED STATES PATENT OFFICE.

JAMES F. ROWLEY, OF CHICAGO, ILLINOIS.

ARTIFICIAL LIMB.

Specification of Letters Patent. Patented Feb. 15, 1921.

1,368,575.

Application filed July 10, 1920. Serial No. 395,237.

To all whom it may concern:

Be it known that I, JAMES F. ROWLEY, a citizen of the United States of America, and a resident of Chicago, county of Cook, 5 and State of Illinois, have invented certain new and useful Improvements in Artificial Limbs, of which the following is a specification.

This invention relates to means for producing the desired action of an artificial limb, and more particularly to controlling devices for bending and straightening a leg. The present invention is of the same 10 general character as that disclosed in applicant's copending application Serial No. 394,062, filed July 6, 1920, but includes certain developments of the structure disclosed in said application for patent.

An object of the invention is to provide 15 a leg controlling mechanism which is operable by movement of the wearer to alternately flex and straighten the leg and which will operate correctly during ordinary walking without special attention of the wearer.

20 A further object of the invention is to provide a construction which is operative due to a single extension of the body of the wearer of the limb to first bend the leg and then straighten it with the end in view of attaining a correct action for walking by the 25 simplest means.

A further object of the invention is to 30 provide a leg straightening device operable by an extension of the body of the wearer and opposed by a resilient leg flexing device, said leg flexing device being arranged to move toward an ineffective position as the leg bends.

These objects are accomplished by the 35 structure shown in the accompanying drawing, in which—

Figure 1 is a sectional view of an artificial leg constructed according to this invention.

40 Fig. 2 is a plan view of the controlling mechanism for the lower leg section.

Fig. 3 is a front view of the entire leg with its suspender.

The aim of this invention is to enable the 45 user of an artificial leg to walk correctly without particular attention to the control of the leg and to enable him to control its action as desired, both in bending and straightening the leg. To this end means 50 is provided whereby upon a forward and rearward movement of the thigh to which

the leg is fitted, the leg alternately straightens and bends to the desired extent. This means comprises the suspender support for the leg and its particular connections with the lower leg section. When the weight of 55 the wearer is on the leg it is maintained in its straightened position, but as the weight is transferred to the remaining leg the straight one first bends slightly, but as it is 60 swung toward its extreme forward position it is again straightened. Both the bending and straightening of the leg may be due to change in tension of the suspender occurring during the act of walking. A tensioning of 70 the suspender first acts upon one side and then the other of the pivotal connection between the leg sections.

The particular construction by which the 75 invention is carried into effect comprises the usual design of leg sections pivotally connected as by a knee bolt, and the lower leg section being provided with an arm or lever by means of which through suspenders this section of the leg may be swung to 80 straightened relation with the thigh section. The outer end of the lever has a roller connection with loops of the supporting suspender. Inwardly of the pivotal connection between the two leg sections the suspender 85 loop also has a roller connection with a leg bending strap or elastic web. By this construction an extension of the body of the wearer of the limb causes the suspender loops to first draw upwardly on the leg flexing web, 90 and after the leg is bent to the desired degree for walking, the continued tensioning of the suspender results in a reverse action, that is, the loop operates on the forward end 95 of the leg straightening lever. The leg straightening lever forms a bearing for the upper end of the leg flexing strap and this bearing is so formed that the loop roller carried at the upper end of the strap will be guided toward the pivotal connection between the leg sections as the leg is bent, and in this manner the resistance of the elastic web is reduced as effort is applied for straightening the leg.

The invention as illustrated in the drawings may be practised by means of a leg construction consisting of a thigh portion 1 and a lower leg portion 2 pivotally connected by a knee bolt 3. Attached to the lower leg section is an arm or lever 4 which may be journaled on the knee bolt and carries at its upper forwardly extending end

a double grooved pulley 5 around which pass the loops 6 of the supporting suspender 7. Rearwardly of the knee bolt 3 the suspender loops pass around pulleys 8. The rectangularly bent rod 9 upon which the pulley 8 is journaled is attached to the upper end of an elastic web 10. This web is secured at its lower end to the lower leg section considerably below and to the rear of knee bolt 3. A pad 11 is carried at the upper end of web 10 for bearing on the curved surface 12 of lever 4.

With the construction described, an upward drawing of the loop 6 by a body motion of the wearer results in tensioning the web 10, but as the knee bends under this action the pad 11 rides upwardly on the curved surface 12 of the lever 4 toward the knee bolt, in which position the web 10 becomes less effective for resisting continued upward motion of loops 6. Such continued motion becomes effective on the forward end of lever 4 and returns the lower leg section in straightened relation 25 with the thigh section. In this manner a single extension of the body of the wearer may result in both bending and straightening the leg. This volitional action is particularly convenient for walking through 30 heavy snow or up stairways or wherever walking is more difficult than normal. In normal walking over a level surface the leg has some pendulum action. When it supports a weight it is of course maintained 35 straight against the resistance of elastic web 10, but when it is relieved of its load the web assists in flexing the leg upon the forward motion of the thigh, but the suspenders tension slightly during this motion and 40 with the forwardly swinging weight of the lower leg section overcome the resistance of web 10 so that the leg is again straightened before the foot reaches the ground.

Although but one specific embodiment of

this invention has been herein shown and described, it will be understood that numerous details of the construction shown may be altered or omitted without departing from the spirit of this invention as defined by the following claims.

50

I claim:

1. An artificial limb, comprising two pivotally connected sections, means for changing the angular relation of said sections, a resilient element opposed to said means and 55 slidably connected therewith to move toward ineffective position during operation of said means.

2. An artificial limb, comprising two pivotally connected sections, a lever to 60 straighten the leg, a resilient element opposed to said lever and slidably connected therewith to move toward ineffective position during operation of said lever.

3. An artificial limb, comprising two 65 pivotally connected sections, means to straighten the leg, a resilient element for opposing said means, said means being arranged to shift said resilient element into inoperative position.

4. An artificial limb, comprising two pivotally connected sections, one means for flexing and one means for straightening the limb, the flexing means having an element which is movable to render the flexing 75 means ineffective for resisting the straightening means after a predetermined action.

5. An artificial limb, comprising two pivoted connected sections, one means for flexing and one for straightening the limb, the 80 flexing means having an element which is movable to a position to render the flexing means less effective for resisting the straightening means after a predetermined action.

85

Signed at Chicago this 7th day of July, 1920.

JAMES F. ROWLEY.
